PALLETIZING PACKAGE FOR STACKED STEERING WHEELS AND THE LIKE

Larry J. Budd, Chicago, Ill., assignor to Pallet Devices, Inc., Des Plaines, Ill., a corporation of Illinois

Application July 16, 1956, Serial No. 597,904

11 Claims. (Cl. 206—65)

This invention relates generally to a new and improved package or carton for carrying the articles in suspension therein.

Manufacturers, in the past, have had difficulty in packaging and shipping steering wheels for an automobile and the like. The reason for the problem has been that steering wheels are odd-shaped, fragile articles, which are relatively easily damaged if they are not properly handled. The present invention relates to a new type of fiber or paper-board carton, which may be economically manufactured and which is especially adapted to carry odd-shaped, fragile articles such as drop-center type of steering wheels in stacked suspension relative to one another.

Accordingly, an object of this invention is to provide a new and improved package for carrying odd-shaped, fragile articles in suspension.

Another object of this invention relates to a new and improved method of packaging steering wheels and the like.

Another object of this invention concerns itself with manufacturing a carton for carrying odd-shaped articles in suspension from a strip of paper-board material, or the like, with a minimum waste of material.

Yet another object of this invention relates to providing a carton for carrying odd-shaped, fragile articles, which may be economically manufactured, at a low cost on a high production basis.

According to the general features of this invention, a shipping package has been provided for carrying a plurality of vertically stacked drop-center type of steering wheels in suspension relative to one another. The package includes super-imposed sections separated from one another by dividers, each having a central opening. Each of the sections has a series of connected side-walls enclosing a central area, with at least two of the side walls being opposed to one another. The opposed side walls each have a plurality of vertically spaced slits opposite one another and defining ledges, and each of the ledges includes spaced, notched portions defining notches with the steering wheels engageable on opposite sides in the notches of the opposed ledges to support and suspend these steering wheels in vertically stacked relation. The lowermost drop-center type of steering wheel in the super-imposed section has a portion extending through the central opening, thereby, utilizing as much of the carton space as is possible.

Another feature of this invention relates to manufacturing the carton from a single strip of material with a minimum of waste.

Still another feature of this invention relates to creasing the ledges to render them yieldable so as to be readily adaptable for receiving portions of the steering wheel in the suspension of the wheels by the carton or section.

Yet another feature of this invention relates to the provision of a package having the shape of a parallelogram and having nested therein a section having a six-sided configuration.

Other objects and features of the present invention will more fully become apparent in view of the following detailed description taken in conjunction with the accompanying sheets on drawings and illustrating therein a single embodiment and within which:

Figure 1 is a perspective view of my carton;

Figure 2 is a layout view of a pre-cut strip in readiness to be folded;

Figure 3 is a plan view of Figure 1 with the cover removed and with only one of the uppermost ledges deflected over the steering wheel.

Figure 4 is a cross-sectional view taken substantially on the line IV—IV of Figure 3 looking in the direction indicated by the arrows: and

Figure 5 is a plan-view of the divider used in my package.

As shown on the drawings:

The reference numeral 10 indicates generally my package which may be made from any suitable flexible material such as reinforced or corrugated fiber board, paper-board, and the like. The package 10 has nested therein super-imposed hollowed-out six-sided cartons or sections 11 and 12 separated by a divider 13. The sections 11 and 12 are adapted to be sandwiched between protective covers 14 and 15, which overlie and underlie the super-imposed stacked sections 11 and 12. The package 10 may be held in assembly by means of steel bands or strips and the like; cover 15 in the present instance comprising a paper-board pallet having legs 16.

The package 10 is especially adapted to carry odd-shaped articles in suspension, out of contact from one another to minimize damage to the same. More specifically, the package lends itself to carrying in stacked relation, one half or full, semi-circular or circular, or square steering wheels, which may be of a drop-center type, and the like in suspension to preclude contact and damage to the steering wheels. The package 10 may be of any suitable shape although excellent results may be attained with the package having a square or rectangular configuration.

Each of the sections 11 and 12 are formed from a single strip of material indicated at 17 in Figure 2. The strip 17 may be formed in steel roll dies and divided up into seven flaps, 18, 19, 20, 21, 22, 23 and 24. As is apparent from Figure 2, flaps 20 and 23 are of the same length as are flaps 19, 21, 22 and 24. Overlapping flap 18 is of a reduced length. The width of all of the flaps 17—24 are the same.

In the formation of the strip, flaps 20 and 23 are each provided with a plurality of vertically spaced, longitudinally extending slits 25, the slits 25 in flap 19 lying in the same plane as the slits in the flap 22. By slitting the flaps 20 and 23, a plurality of vertically adjacent slit portions or ledges 26, are provided. Each of the ledges include spaced notched out portions 27 defining notches or sub-ledges 28. To lend flexibility to the ledges 26 so that the notches 28 may be readily engaged with handle portion 29 of the steering wheel 17, they are creased at 30 and 31.

After the strip 18 has been creased and cut out in the manner aforesaid, the strip is then folded along scorelines 32, 33, 34, 35, 36, and 37 with the flap 18 stapled or otherwise connected to the flap 24 in overlapping relation enclosing a central area.

To assemble the steering wheel 17 into the sections 11 and 12, the opposed ledges 26 on flaps 20 and 23 are deflected outwardly with handle portion 29 of the wheel engaged in the notches 28 of the ledge so exposed. The ledge 26 immediately above is then moved inwardly over the ledge immediately above. By starting with the lowermost ledges 26, and working upwardly with the successive ledges, the steering wheels 17 may be

rapidly positioned in the cartons 11 and 12. The uppermost ledge 26a (Figures 2 and 3) in section 11 may or may not be notched as is desired, but serves as do each of the other slit portions 26 as means to interlock the wheels 17 by bearing against the top side of the wheel while the wheels rest in the notches 28 as is shown in Figure 3, where one of the ledges has been deflected to overlie the wheel, while the other is still out of position.

In order to utilize as much space as possible in the cartons, the divider 13 is placed between the sections. The divider 13 has a central opening 38 through which drop-center portion 39a of the steering wheel 17 may extend into the carton immediately below. By utilizing the intermediate layer 13, many inches of carton space are utilized, which would otherwise be lost.

The rectangular covers 14 and 15 may be made in the same manner. In other words, a single flat strip may be cut out and provided with opposed longer and shorter flaps 39 and 40. Ends 41 of the longer flaps 39 may be folded over to overlap the shorter flaps 40 and stapled or otherwise secured therewith. Provided on the lower cover 15 at the four corners are the legs 16, which may be of any suitable construction, and which serve to convert the cover to a pallet.

While I have shown my sections 11 and 12 as each having five ledges 26, it will be appreciated that any suitable number of ledges may be employed. Also, while I have shown only two sections 11 and 12 disposed between the cover 14 and the pallet 15, any suitable number of sections may be super-imposed in stacked relationship.

It will be understood that modifications and variations may be effected without departing from the scope of the novel concepts of the present invention.

I claim as my invention:

1. A shipping package, a plurality of vertically stacked drop center type of steering wheels supported by the package, said package including super imposed sections separated from one another by a divider having a central opening, each of said sections having a series of connected sidewalls enclosing a central area, at least two of said sidewalls being opposed to one another and each having a plurality of vertically spaced slits opposite one another and defining ledges, each of said ledges including spaced notched portions defining notches with the steering wheels engaged on opposite sides in said notches of said opposed ledges to support and suspend the steering wheels in vertically spaced stacked relation, the lowermost drop center type of steering wheel in said super imposed section having a portion extending through said central opening.

2. A shipping package for carrying in suspension a plurality of vertically stacked drop center type of steering wheels, said package including super imposed sections, each of said sections having a series of connected sidewalls enclosing a central area, at least two of said sidewalls being opposed to one another and each having a plurality of vertically spaced slits opposite one another and defining sections having lower edges and upper ledges, each of said ledges including spaced notched portions defining notches with the steering wheels engaged on opposite sides in said notches of said opposed ledges to support and suspend the steering wheels in vertically spaced stacked relation, said lower edges along with said sections being movable into and out of overlying relation with respect to the steering wheel disposed immediately below to preclude vertical displacement, said package having a bottom underlying the lowermost section and a cover overlying the uppermost section to further enclose said shipping package.

3. A shipping package, a plurality of vertically stacked drop center type of steering wheels supported by the package, said package including super imposed sections, each of said sections having a series of connected side-

walls enclosing a central area, at least two of said sidewalls being opposed to one another and each having a plurality of vertically spaced slits opposite one another and defining ledges, each of said ledges including spaced notched portions defining notches with the steering wheels engaged on opposite sides in said notches of said opposed ledges to support and suspend the steering wheels in vertically spaced stacked relation, said ledges being yieldable to enable notched portions to be readily engaged with the steering wheels.

4. A shipping package for carrying in suspension a plurality of vertically stacked drop center type of steering wheels, said package including super imposed sections each of said sections having a series of connected sidewalls enclosing a central area, at least two of said sidewalls being opposed to one another and each having a plurality of vertically spaced slits opposite one another and defining ledges, each of said ledges including spaced notched portions defining notches with the steering wheels engaged on opposite sides in said notches of said opposed ledges to support and suspend the steering wheels in vertically spaced stacked relation, said ledges having creases to render said ledges flexible enabling portions of the steering wheels to be engaged in the notches defined by each of said notched portions on each of said ledges.

5. A shipping package to carry a plurality of drop center type of steering wheels, said package having means to maintain the steering wheels in vertically spaced suspended relation to one another, said means including a series of vertically adjacent independently yieldable and adjustable sections each having vertically spaced upper and lower edges with the upper edges having notches to receive segments of the steering wheels to suspend the steering wheels in vertically spaced relation.

6. A paper board shipping package for carrying a plurality of articles in suspension, said package including a section having connected side walls, vertically spaced slits in said side walls dividing said side walls into a plurality of vertically adjacent yieldable ledges, said yieldable ledges having notches in which portions of the articles may be engaged to separately suspend each article in overlying spaced relation to adjacent articles.

7. A paper board shipping package for carrying a plurality of articles in suspension, said package including a section having connected side walls, vertically spaced slits in said side walls dividing said side walls into a plurality of vertically adjacent yieldable ledges, said yieldable ledges having notches in which portions of the articles may be engaged to separately suspend each article in overlying spaced relation to adjacent articles, said section having two sets of parallel sides in addition to the slit side walls.

8. A paper board shipping package for carrying a plurality of articles in suspension, said package including a section having connected side walls, vertically spaced slits in said side walls dividing said side walls into a plurality of vertically adjacent yieldable ledges, said yieldable ledges having notches in which portions of the articles may be engaged to separately suspend each article in overlying spaced relation to adjacent articles, said package having the shape of a parallelogram, and said ledges being dished inwardly when the articles are suspended therefrom so as to laterally angle the notches with respect to the package in order that the articles may be carried substantially within the confines of the section.

9. The package of claim 6 further characterized by said yieldable ledges having vertically extending creased areas to enable the ledges to be readily bodily deflected into engagement with the steering wheel.

10. The package of claim 6 further characterized by said ledges being connected to said package at their longitudinally opposite ends and with the ledges being vertically scored at their opposite ends to allow the ledges to be bodily displaced.

11. The package of claim 6 further characterized by
said ledges being connected to said package at their hori-
zontally opposite ends and with said notches being dis-
posed between said ledges.
